ALFRED A. BRIGGS, OF NEW YORK, N. Y., ASSIGNOR OF ONE-HALF TO JOSIAH A. BRIGGS,
OF NEW YORK, N. Y.

FLUSH TANK FIXTURE

Application filed February 4, 1931. Serial No. 513,267.

This invention relates to flush tank fixtures and particularly to valve mechanism and controlling mechanism for initiating the flow of or discharge of water from the tank.

5 One of the objects of the invention is to provide a tank fixture of the character described that is simple in construction, comprises few parts, and may be economically manufactured.

10 Another object of the invention is to provide a fixture that is positive and quiet in operation and in which the parts are so constructed and arranged that they will not be thrown out of adjustment in use.

15 Another object of the invention is to provide a construction that is rugged and will operate effectively and quietly without the use of packings, washers or similar devices.

Another object of the invention is to provide 20 a flush tank fixture so constructed and arranged that successive discharges from the tank will be obtained.

Another object of the invention is to provide 25 a flush tank fixture which will operate automatically and intermittently.

Further objects of the invention will appear from the following specification taken in connection with the drawings, which form a part of this application, and in which

30 Fig. 1 is a sectional elevation of a tank having a fixture therein constructed in accordance with the invention;

Fig. 2 is a sectional elevation of the structure shown in Fig. 1 taken substantially on line 2—2 of Fig. 1;

Fig. 3 is a sectional elevation of a part of the float shown in Fig. 1, on a somewhat enlarged scale;

Fig. 4 is a top plan of the parts shown in 40 Fig. 1;

Fig. 5 is a sectional elevation of one of the valve mechanisms taken substantially on line 5—5 of Fig. 2; and

Fig. 6 is a sectional elevation of the other 45 valve mechanism taken substantially on line 6—6 of Fig. 2.

The invention briefly described consists of a flush tank fixture comprising a U-shaped flush or outlet pipe, one leg of the U-shaped 50 pipe extending downwardly into the tank

and receiving water therefrom and the other leg extending downwardly through the bottom of the tank. A valve casing communicates with the inlet leg of the pipe and when the valve in the casing is opened, water from the pressure main is injected into the inlet leg and initiates the flow of water through the flush pipe. The water under pressure forces the air and water around the bend of the U-shaped flush pipe and sets in operation the siphon action, whereby the tank will be emptied. In the form of the invention illustrated, the flow of water through the valve chamber into the flush pipe and also the flow into the tank to replenish the tank are valve controlled. The float which controls the main inlet valve may be constructed for automatic operation.

Further details of the invention will appear from the following description.

The invention illustrated and to be described in this application constitutes a simplification of and an improvement on the invention covered by Patents Nos. 1,519,188 to Alfred A. Briggs, granted December 16, 1924 and 1,769,617 issued to Alfred A. Briggs and Josiah A. Briggs, July 1, 1930.

In the embodiment of the invention illustrated in the drawings, there is shown a flush tank 10 having secured thereto a U-shaped siphon or flush pipe having its inlet leg 11 extending downwardly to a position adjacent the bottom of the tank and having its outlet leg 12 extending through the bottom of the tank about four inches to form an air chamber between the bowl and the bottom of the tank. The lower end of the outlet leg 12 discharges into a pipe 9 secured to the bottom of the tank and surrounding and spaced from the end of pipe 12. As shown in Fig. 1, the inlet leg 11 is slightly larger in cross section than the outlet leg 12.

The inlet leg 11 of the flush pipe is interrupted, as shown at 13, and an annular casing 14 is secured to this portion of the leg 11. The casing 14 has an annular chamber 15 surrounding the leg 11 and has a conical wall 16 disposed above the conical upper end 17 of the lower portion of the leg 11. The casing 14 is connected, as shown at 18, to the upper

portion 11A of the inlet leg 11 and the lower portion of the inlet leg is adjustably threaded, as shown at 19, to the casing. A lock nut 20 secures the lower portion of the leg 11 in adjusted position.

From the foregoing description it will be seen that a conical opening is formed between the upper end 17 of the lower portion of the inlet leg and the portion 16 of the inner wall 10 of the casing.

A pipe 26 is connected at one end to the casing 14 and at its opposite end to a T-shaped coupling 27 which communicates at one end with a valve casing 28 having upper and lower chambers 29 and 30. The upper chamber 29 of the valve casing 28 receives water from a pressure main 31 which, as shown at 32, extends downwardly through the bottom of the tank. The other end of coupling 27 20 communicates with a valve controlled water pipe 95 for refilling the tank, hereinafter described.

A valve port 38 establishes communication between the chambers 29 and 30 and the flow of liquid through this port is controlled by a valve 40 which is adapted to seat on the port 38.

Valve 40 has connected thereto a valve stem 41 having an enlarged portion 42 slidably mounted in a tubular extension 43 which projects downwardly from the valve casing 28. The enlarged portion 42 of the valve stem has a slot 45 therethrough and the tubular extension 43 is slotted to permit the passage therethrough and through the slot 45 of a valve control lever 50. The lever 50 is pivoted at 51 on lugs carried by the tubular extension 43 and has a circular portion 52 disposed in the slot 45 of the enlarged portion of the 40 valve stem.

The lower end of the tubular extension 43 is closed by a plug 55 and the portion of the valve stem below the slot 45 has formed therein a conduit having a downwardly extending portion 56 and a laterally extending portion 57, as shown in Fig. 5. 56 extends above 57 to form an air pocket in which air is compressed, which takes care of the last one-sixteenth inch of valve travel. The portion 57 of the conduit is so located that when the valve is opened by the lever and the valve stem is disposed in its uppermost position, the outer end of the portion 57 of the conduit will communicate with the slot or opening in 55 the extension 43, through which the lever 50 passes, as shown in dotted lines, (Fig. 5).

A conduit 39 communicates at one end with the chamber 30 in the valve casing and at its opposite end, after the lower end of the enlarged portion of the valve stem has started its upward movement, with the lower end of the tubular extension.

One end of the lever has formed therein a vertical slot 67 through which extends a link 68 having adjustably mounted on its lower

end below the lever, a nut 69. The upper end of the link 68 is connected to a crank 70 mounted on a spindle 71 journaled in a wall of the tank and extending therethrough. The outer end of the spindle 71 has secured thereto a handle 75, by means of which the crank and spindle can be rotated in either direction to lift the lever 50 and open the valve 40.

The parts thus far described are the same as those shown in Patent No. 1,769,617.

53 is a vertical guide rod on which a sleeve 54 is slidably mounted and to which the end of lever 50 is connected by a slot and pin arrangement. A float 60 is provided which 80 comprises a cylindrical casing 58 having a cross-disc 59 which is affixed to sleeve 54. These parts form an inverted cup-like air chamber 61. 62 is a cylindrical cup fitted within the casing 58 and having a bottom 85 63 which rests on the disc 59. 64 is a siphon, the inlet end of which is near the bottom 63. Its outlet leg 65 passes through the bottom 63 and through an arcuate slot in disc 59 and to a point at or near the lower end of the casing 58.

80 is a chamber connected by a port 81 with chamber 30 and controlled by a valve 82. The latter has a stem 83 slidably mounted in a boss 84 at one end of coupling 27. 85 is a lever pivoted at 86, having a circular portion 87 in a slot in valve stem 83 and with its end connected by a slot and pin arrangement with sleeve 88 slidably mounted on a vertical rod 89. 90 is a float of comparatively small size which comprises an open ended cylindrical casing 91 with a cross-disc 92 intermediate its ends. 93 is a siphon passing from a point near the disc 92 through the disc to a point at or near the lower end of casing 91. 94 is an adjustable stop in the path of movement of lever 85 to limit the upward travel of float 90 to a point with its upper edge below the water level A, B shown in dotted lines in Fig. 6, when valve 84 is depressed to open port 81.

When the water rises in tank 10, under conditions to be described presently, air entrapped under disc 92 will cause float 90 to rise until its movement is arrested by stop 94. Shortly thereafter the upper part of float 90 will fill with water and the float 90 will descend to its position shown in full lines in Fig. 6 to raise valve 84 to close port 81.

The float 60 is maintained in the position shown in Fig. 1 by the air in chamber 61, with the upper cup 62 slightly above the upper water level A, B. In this position it maintains the valve 40 on its seat. This valve may be opened by turning the handle 75 to rock the lever 50. However, the initial movement of lever 50 brings the upper edge of cup 62 below the water level so that the cup fills and causes the movement of lever 130

50 to be completed, if this is not accomplished manually.

The water from the pressure main 31 will thus be permitted to flow from the chamber 5 29 into the chamber 30 of the valve casing. The water then flows through the coupling 27 and pipe 26, into the chamber 15 surrounding the inlet leg of the U-shaped flush pipe.

10 The pressure of the water will direct a conical stream into the inlet leg through the conical opening between the surfaces 16 and 17, and this stream will positively lift the water in the upper end 11A of the U-shaped 15 connecting coupling between the legs 11 and 12. This column of water will force before it any air in the U-shaped flush pipe and will completely fill the outlet leg, due to the difference in diameter between the inlet and outlet legs of the flush pipe.

20 When the water in tank 10 gets below the discharge legs of siphons 64 and 93, the water in the upper parts of floats 60 and 90 will be discharged through them. Then as water is 25 supplied to tank 10, first through the leg 11 of the main siphon, both floats will rise. It is not desirable to have all of the tank water supplied through the conical spray opening between the surfaces 16 and 17 as this would 30 initiate an undesired siphon discharge through the flush pipe 11, 12, and so the float 90 is arranged to open valve 84 to provide another path for water to the tank through port 81 and discharge pipe 95.

35 When it is desired to effect automatic intermittent actuation, the cup 62 of float 60 is rotated to bring an orifice 95 in its wall, in alignment with an orifice 96 in the wall of cylinder 58. When the water line A—B rises above 40 these orifices, water will leak into the cup gradually. As it rises therein, air will be entrapped in an inverted cup 97 from the center of which depends a valve 98 which closes a port 99 through the bottom 63 of cup 62. 45 After a predetermined time this will cause cup 97 and valve 98 to rise, thus quickly permitting the escape of the air which is entrapped in cylinder 58 under its disc 59. Float 60 will then sink to open valve 40 and 50 this will effect the flush and refill operations previously described.

The specific embodiment of the invention herein shown and described is for illustrative purposes and I intend no limitations other than those imposed by the appended claims.

What I claim is:

1. In a flush tank fixture, a tank, a U-shaped outlet pipe having an inlet leg extending to a position adjacent the bottom of the tank and an outlet leg extending through the bottom of the tank, a pressure main adapted to supply water to said outlet pipe and to the tank, a valve arranged to control the water supply, a float arranged to control the

valve, said float comprising an open ended cylinder, a subdividing disc intermediate the ends thereof, the upper edge of said cylinder being slightly above the upper water level in the tank, manual means for depressing the float to initiate the opening of the valve and to cause the float to sink, and means for permitting the water to escape gradually from the upper part of said cylinder to restore the buoyancy of the float.

2. In combination with the valve of a flush tank fixture, a float comprising an open ended cylinder, a subdividing disc intermediate the ends thereof, the upper edge of said cylinder being slightly above the upper water level in the tank, manual means for depressing the float to initiate the opening of the valve and to cause the float to sink, and means for permitting the water to escape gradually from the upper part of said cylinder to restore the buoyancy of the float.

3. In a flush tank fixture, a tank, a U-shaped outlet pipe having an inlet leg extending to a position adjacent the bottom of the tank and an outlet leg extending through the bottom of the tank, a pressure main adapted to supply water to said outlet pipe and to the tank, a valve arranged to control the water supply, a float arranged to control the valve, said float comprising an open ended cylinder, a subdividing disc intermediate the ends thereof, and means for admitting water gradually to the part above said disc to cause said float to sink.

4. In a flush tank fixture, a tank, a U-shaped outlet pipe having an inlet leg extending to a position adjacent the bottom of the tank and an outlet leg extending through the bottom of the tank, a pressure main adapted to supply water to said outlet pipe and to the tank, a valve arranged to control the water supply, a float arranged to control the valve, said float comprising an open ended cylinder, a subdividing disc intermediate the ends thereof, means for admitting water gradually to the part above said disc to cause said float to sink, and means for permitting the water to escape gradually from the upper part of said cylinder to restore the buoyancy of the float.

5. In a flush tank fixture, a tank, a U-shaped outlet pipe having an inlet leg extending to a position adjacent the bottom of the tank and an outlet leg extending through the bottom of the tank, a pressure main adapted to supply water to said outlet pipe and to the tank, a valve arranged to control the water supply, a float arranged to control the valve, said float comprising an open ended cylinder, a subdividing disc intermediate the ends thereof, means for admitting water gradually to the part above said disc to cause said float to sink, and a siphon extending through said disc arranged to withdraw the water gradually from the upper part of said

cylinder to restore the buoyancy of the float.

6. In a flush tank fixture, a tank, a U-shaped outlet pipe having an inlet leg extending to a position adjacent the bottom of the tank and an outlet leg extending through the bottom of the tank, a water pressure valve chamber, a pressure supply main connected therewith, a conduit between the chamber and said inlet leg, a valve controlling said conduit, an outlet passage from said chamber to the tank, a valve controlling said passage, a main float connected with said conduit controlling valve, means for causing said main float to sink to open its valve, an auxiliary float connected with said passage-controlling valve arranged to rise to open its valve as water runs into the tank through said inlet leg and to sink to close its valve when the water reaches a predetermined level in the tank.

7. In a flush tank fixture, a tank, a U-shaped outlet pipe having an inlet leg extending to a position adjacent the bottom of the tank and an outlet pipe extending through the bottom of the tank, a water pressure valve chamber, a pressure supply main connected therewith, a conduit between the chamber and said inlet leg, a valve controlling said conduit, an outlet passage from said chamber to the tank, a valve controlling said passage, a main float connected with said conduit controlling valve, means for causing said main float to sink to open its valve, an auxiliary float connected with said passage-controlling valve arranged to rise to open its valve as water runs into the tank through said inlet leg and to sink to close its valve when the water reaches a predetermined level in the tank, each of said floats comprising an open ended cylinder, a subdividing disc intermediate the ends thereof, a siphon through the disc arranged to withdraw water gradually from the upper part of the cylinder.

8. In a flush tank fixture, a tank, a U-shaped outlet pipe having an inlet leg extending to a position adjacent the bottom of the tank and an outlet leg extending through the bottom of the tank, a water pressure valve chamber, a pressure supply main connected therewith, a conduit between the chamber and said inlet leg, a valve controlling said conduit, an outlet passage from said chamber to the tank, a valve controlling said passage, a main float connected with said conduit controlling valve, means for causing said main float to sink to open its valve, an auxiliary float connected with said passage-controlling valve arranged to rise to open its valve as water runs into the tank through said inlet leg and to sink to close its valve when the water reaches a predetermined level in the tank, each of said floats comprising an open ended cylinder, a subdividing disc intermediate the ends thereof, a siphon through the disc arranged to withdraw water gradually from the upper

part of the cylinder, the upper edge of the main float being slightly above the upper water level in the tank when said main float is in its valve closing position, and means for limiting the uppermost valve opening position of the auxiliary float to keep its siphon below the upper water level in the tank.

9. In a flush tank fixture, a tank, a U-shaped outlet pipe having an inlet leg extending to a position adjacent the bottom of the tank and an outlet leg extending through the bottom of the tank, a water pressure valve chamber, a pressure supply main connected therewith, a conduit between the chamber and said inlet leg, a valve controlling said conduit, an outlet passage from said chamber to the tank, a valve controlling said passage, a main float connected with said conduit controlling valve, means for causing said main float to sink to open its valve, an auxiliary float connected with said passage-controlling valve arranged to rise to open its valve as water runs into the tank through said inlet leg and to sink to close its valve when the water reaches a predetermined level in the tank, each of said floats comprising an open ended cylinder, a subdividing disc intermediate the ends thereof, a siphon through the disc arranged to withdraw water gradually from the upper part of the cylinder, the upper edge of the main float being slightly above the upper water level in the tank when said main float is in its valve closing position, and adjustable means for limiting the uppermost valve opening position of the auxiliary float to keep its siphon below the upper water level in the tank.

10. A float for controlling the valve of a flush tank fixture comprising an open ended cylinder, a subdividing disc intermediate the ends thereof, means for permitting water to enter the upper part of said cylinder to cause the float to sink, and means for permitting the water to escape from said upper part of the cylinder to restore the buoyancy of the float.

11. A float for controlling the valve of a flush tank fixture comprising an open ended cylinder, a subdividing disc intermediate the ends thereof, means for permitting water to enter slowly the upper part of said cylinder to cause the float to sink, and means for permitting the water to escape slowly from said upper part of the cylinder to restore the buoyancy of the float.

12. A float for controlling the valve of a flush tank fixture comprising an open ended cylinder, a subdividing disc intermediate the ends thereof, means for permitting water to enter the upper part of said cylinder slowly, means controlled by the water thus entering said upper part of the cylinder, for releasing the air entrapped under said disc, to cause the float to sink rapidly, and means for permitting the water to escape slowly from said upper

per part of the cylinder to restore the buoyancy of the float.

13. A float for controlling the valve of a flush tank fixture comprising an open ended cylinder, a subdividing disc intermediate the ends thereof, means for permitting water to enter the upper part of said cylinder slowly, a secondary float controlled valve in the upper part of the cylinder controlled by the water thus entering said upper part of the cylinder, for releasing through the disc, the air entrapped in the lower part of the cylinder, to cause the float to sink rapidly, and means for permitting the water to escape slowly from said upper part of the cylinder to restore the buoyancy of the float.
